US0D1009771S

(12) **United States Design Patent** (10) **Patent No.:** **US D1,009,771 S**
(45) **Date of Patent:** ** **Jan. 2, 2024**

(54) **TIRE**

(71) Applicant: **Guangzhou Nedong Information Technology Co., Ltd.**, Guangdong (CN)

(72) Inventors: **Chunru Zhang**, Guangzhou (CN); **Haiming Sun**, Guangzhou (CN)

(73) Assignee: **Guangzhou Nedong Information Technology Co., Ltd.**, Guangdong (CN)

(**) Term: **15 Years**

(21) Appl. No.: **29/782,299**

(22) Filed: **May 6, 2021**

(30) **Foreign Application Priority Data**

Apr. 1, 2021 (CN) 202130181938.9

(51) **LOC (14) Cl.** **12-15**

(52) **U.S. Cl.**

USPC **D12/501**; D12/503

(58) **Field of Classification Search**

USPC D12/501, 604, 579, 503, 512, 568, 605, D12/900, 500, 502, 507; D21/779

CPC B60C 11/0306; B60C 13/00; B60C 1/00

See application file for complete search history.

(57) **CLAIM**

The ornamental design for a tire, as shown and described.

DESCRIPTION

FIG. 1 is a perspective view of a first embodiment of a tire showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof;

FIG. 9 is an enlarged view of portion 9 shown in FIG. 5;

FIG. 10 is a perspective view of a second embodiment of a tire showing our new design;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is another perspective view thereof; and,

FIG. 18 is an enlarged view of portion 18 shown in FIG. 14.
